SPARK PLUG

Application filed April 3, 1929. Serial No. 352,184.

This invention relates to new and useful improvements in spark plugs which are especially adapted for use in connection with automobile internal combustion engines.

It is a known fact, that when starting an internal combustion engine while it is cold, by means of an electric motor that is supplied with electric current from a battery, which simultaneously is furnishing current for the ignition system of said engine, an arrangement that is generally embodied in the power plant of an automobile, that this battery is often overloaded by the heavy discharge that the starting motor imposes upon it. This heavy discharge is still further increased in cold weather when the oil in the engine is congealed and resists the efforts of the starting motor to a greater extent, effecting a considerable lowering of the voltage available for ignition of the engine. Frequently the gap formed between the spark plug electrodes, too wide for the purpose of starting the engine, causes failure to produce a spark until after the engine has been "turned over" a number of times and the resistance of the crank case oil has thereby been reduced. This is particularly true when the battery is not fully charged.

One of the principal objects of my invention is to provide a spark plug which will vary automatically the size of the spark gap in accordance with the temperature of the engine.

Another object of the invention lies in the provision of a spark plug having two electrodes normally forming therebetween two spark gaps of relatively smaller and larger sizes, one of the electrodes being movable under the application of increased heat to increase the smaller gap to a size at least equal to the size of the larger gap without varying the size of said larger gap.

A further object of my invention is to provide the insulator of the spark plug with a recess which surrounds the central electrode in such a manner as to reduce to a minimum the danger of shortcircuiting between the central electrode, the insulator and the conductor shell to which the ground electrode is fixed.

A still further object of the invention is to provide means associated with the recess

which surrounds the central electrode for reducing to a minimum the accumulation of carbon within said recess.

With these and other objects in view which will more fully appear, the nature of the invention will be more clearly understood by following the description, the appended claims, and the several views illustrated in the accompanying drawings.

In the drawings:

Figure 1 is a longitudinal sectional view of a spark plug embodying the preferred form of my invention,

Figure 2 is a complete view of the inner end thereof,

Figure 3 is a view similar to Figure 1 but showing another form of my invention,

Figure 4 is a complete view of the inner end thereof,

Figure 5 is a view similar to Figure 1 but showing another form of my invention,

Figure 6 is a complete view of the inner end thereof,

Figure 7 is a view partly in side elevation and partly in section showing another form of my invention,

Figure 8 is a complete view of the inner end thereof, and

Figure 9 is a complete end view of another form of my invention showing the structures of Figures 5 and 7 combined.

Like reference numerals designate corresponding parts throughout the several figures of the drawings.

Referring to the drawings and particularly to Figures 1 and 2, I have shown a spark plug which comprises a conductor shell A, an insulator B mounted therein and retained in position by a gland nut C, the inner end 5 of the insulator being disposed within the shell and the outer end 6 of the insulator projecting for a considerable distance beyond the gland nut. The outer end 6 of the insulator is provided with an axial opening 7 which communicates with a longitudinally and axially located recess 8, the latter extending from the inner end 5 to a point beyond the gland nut C where it forms a resultant end wall or shoulder 9.

Attached to the inner end of the shell is

a ground electrode 10 having a longitudinally extending attaching shank 11 and an inwardly radially extending arm 12. Axially disposed within the recess 8 of the insulator B is a central electrode 13 comprising a rod 14 of copper or of other suitable metal, which will expand and contract under temperature changes, and a reduced extension 15 which is preferably a separate part fitted into an axial bore in the inner end of the rod. The rod 14 is substantially co-extensive with the insulator B and the outer end of the rod is removably fitted within the axial opening 7 thereof. A flange 16 on the rod 14 is located within the recess 8 and cooperates with the end wall or shoulder 9 to prevent outward movement of the rod relative to the insulator. The outer end of the rod 14 projects beyond the insulator B and is threaded as at 17. A washer 18 surrounds the threaded outer end of the rod 14 and bears against the end of the insulator, and clamping nuts 19 have threaded engagement with the threaded portions 17 of the rod for clamping the flange 16 tightly against the shoulder 9. Thus the central electrode 13 may be readily positioned in the insulator B or removed therefrom. A terminal nut 20 is also engaged with the threaded portion 17 of the rod 14 for cooperation with the clamping nuts 19 to secure a lead wire to the central electrode. If desired, suitable packing may be interposed between the shoulder 9 and the flange 16. Extension 15 includes a shank 21 and an inwardly and radially extending arm 22. The shanks 11 and 21 of the two electrodes together with the arms 12 and 22 thereof, are all disposed in a common plane and the arms 12 and 22 are arranged in slightly overlapping relation so as to form therebetween a variable spark gap X. The terminal end of the arm 12 is spaced from the shank 21 to form a substantially constant spark gap Y. By "substantially constant spark gap" I mean a gap whose width varies only to a negligible extent incident to the expansion of the arm 12 of the electrode 10. This electrode is formed of a metal having a low coefficient of expansion such as that possessed by electrodes used in ordinary spark plugs in which the single spark gap is necessarily substantially constant. The variation in the width of the gap Y is negligible, whereas there is an appreciable variation in the width of the gap X at different temperatures. The substantially constant spark gap Y is preferably of standard width, whereas the variable spark gap X is normally considerably narrower than the substantially constant gap Y. Therefore, I have provided a relatively narrow gap X and a relatively wide gap Y. Thus when the engine is first started, the spark will jump the gap X from the arm 22 to the arm 12 and as the engine gets warmer, the central electrode 13 will expand longi-

tudinally and consequently the spark gap X will be automatically increased until said gap equals the substantially constant gap Y at which time the spark will jump across either or both gaps. If the central electrode 70 is further elongated by reason of its inherent expansion the spark will then only jump across the substantially constant gap Y. The diameter of the recess 8 in the insulator is considerably greater than the diameter 75 of the central electrode 13 and consequently an air space is formed around that portion of the electrode which is located within the recess. Thus the rod 14 of the central electrode will become completely surrounded by 80 high compressed gases at the time of each spark, and these compressed gases serve as an additional insulation between the rod and gland nut. This insulation is especially ad- 85 vantageous should the insulator B be formed of porcelain or other porous material. By reason of the recess extending beyond the gland nut C, I have reduced to a minimum the possibility of shortcircuiting between the central electrode and the gland nut. 90

It is to be noted that the minimum distance between the wall of the recess 8 and the rod 14 within the recess is greater than the distance of either spark gap X or Y. This is especially valuable in preventing shortcircuiting, as above noted, for the reason that porcelain insulators very soon absorbs carbon. The microscopic cracks in the glaze become filled with carbon which penetrates the main body of the porcelain and soon causes it to become useless as an insulator. It is desirable, therefore, to prevent carbon from accumulating in the insulator recess 8 as it would tend to lessen the space between the rod 14 and the wall of the recess, and would eventually bridge said space, shutting out the compression of the engine, and also nullifying the insulating property of the insulator. Furthermore the recess 8 should be kept clear of carbon to permit the heat of the exploding 105 gases to reach the rod 14 and for this reason I have provided a check valve which will now be explained. 110

The central electrode 13 is guided during its period of expansion and contraction by a 115 centering washer 23 which is preferably formed of porcelain or other insulating material. This washer 23 is secured to the electrode 13 by being mounted on the reduced portion 15 and being clamped between a 120 flange 24 fixed to the shank 21 and the adjacent end of the rod 14. Thus the guide washer 23 is movable with the central electrode 13 when the latter expands and contracts and has slidable engagement with the wall of the 125 recess 8. This washer 23 is provided with a series of openings 25 which afford communication between the cylinder of the engine and the recess 8 of the spark plug. A check valve 26 is located within the recess 8 and is slid- 130

ably mounted on the rod 14 for cooperation with the openings 25. A coil spring 27 is disposed around the rod 14 and one end bears against the valve 26 and the other end bears 5 against a flange 28 formed on said rod and functions to yieldably retain the valve in its closed position.

When the engine is being started, either by the usual starter or by a crank, a charge of gas 10 mixture is drawn into the cylinders. This charge is compressed by the upward stroke of the pistons and this compressed charge forces the valve 26 to be unseated and some of the compressed mixture is thereby directed 15 into recess 8 of the insulator. At this time the ignition spark occurs and causes the explosion in the combustion chamber, the exploded gases passing into the recess 8 through the openings 25. Immediately after the explosion the check valve will close automatically by means of the spring 27 and by reason of the pressure being equal on both sides of the valve. The closure of the valve will thereby trap the burned gases at near the explosion 20 compression within the recess 8. The piston during the exhaust stroke thereof will force out of the cylinder all burned gases which have not been trapped within the recess 8. When the cycle of operation is repeated, fresh 25 gases will not enter the recess 8, except for a negligible quantity, because of the presence of the burned gases already located within the recess. Consequently the actual flame of the explosion, which will occur only where 30 there are ignitable gases, and which is the agent that causes carbon to be deposited, will not reach into the recess 8 after the first few combustion operations have taken place. Sufficient heat at the time of the explosions 35 will enter through openings 25, due to the compression being stronger than the resistance of the spring 27, and consequently the rod 14 will become heated as the engine functions.

Referring to Figures 3 and 4 which show another form of my invention, I have disclosed a conductor shell A, an insulator D arranged therein and held against movement by a gland nut C. The insulator D is formed 40 with a recess 29 similar to the recess 8. A ground electrode 10 is fixed to the shell A and a central electrode 30 is disposed within the recess 29 and is provided with a reduced extension 15 for cooperation with the ground 45 electrode 10. The central electrode 30 has its outer end mounted in an axial opening 31 formed in the insulator and is held against longitudinal movement relative to the insulator by an expanded socket 32 formed on the 50 end of a projecting rod 33. The socket 32 is disposed within a recess 34 formed in the outer end of the insulator and a packing 35 of cement or other suitable material is disposed within the recess around the socket. 55 A cap 36 is placed over the outer end of the

insulator D and a packing 37 is placed between them. The rod 33 is threaded for engagement with a clamping nut 38 and also threaded on the rod and cooperating with the clamping nut 38 is a clamping nut 39 for 60 securing a lead wire therebetween. The inner end of the rod 30 is guided in its longitudinal movements during expansion and contraction by reason of a plurality of guide or centering arms 40 which are preferably 65 integral with the insulator body. These arms are relatively narrow so as to form resultant spaces 41 therebetween for permitting the heat to pass into the recess 29 and thereby directly affect the central electrode.

By reference to Figures 5 and 6, the form 70 therein shown includes a conductor shell A, an insulator D mounted therein and a gland nut C. The insulator D is formed with a recess 42 similar to the recesses 8 and 29. Fixed 75 to the inner end of the conductor shell A is a ground electrode 43 which includes an attaching shank 44, an inwardly and radially extending arm 45, and a terminal arm 46 which extends at right angles to the longitudinal axis of the arm 45. Located within the recess 42 is a central electrode 47 which includes a substantially non-expansile rod 48 and an appreciably expansile rod 49, the rods being spot welded or otherwise rigidly 80 connected as at 50, 50. The outer end of the central electrode is connected to a socket 32 in the same manner as described in connection with the form shown in Figure 3. The inner end of the rod 48 extends beyond the terminal 85 arm 46. Opposite guides 51, 51, preferably formed integral with the insulator D, extend inwardly from the inner end of the recess 42 and function to guide the central electrode during its expansion and contraction, and 90 also serving to maintain the movement of the electrode in a fixed plane. Thus when the engine is operated and the expansile rod 49 becomes heated, said rod will elongate and cause the outer end of the rod 48 to be moved 95 downwardly away from the arm 45 and thereby vary the spark gap X, and at the same time maintain substantially constant the spark gap Y between the end of the rod 48 and the terminal arm 46.

In the form illustrated in Figures 7 and 8, 100 I have provided a conductor shell A, an insulator E mounted therein and held against movement by a gland nut C. The insulator E is formed with a longitudinal opening 52 which extends substantially throughout the length of the insulator and mounted in this opening is a central electrode 53 having at its inner end a reduced extension 54 which includes an attaching shank 55 and an arm 56 which extends inwardly and radially therefrom. The inner end of the conductor shell A is formed with an interior seat 57 and mounted in this seat is a coiled electrode 58 having one end 59 fixed within an opening formed in 105

the shell. The outer end of the coil terminates in a longitudinally extending shank 60 which in turn is bent to form an arm 61 and a terminal arm 62 arranged at right angles to the arm 61 and extending inwardly and in parallelism with the arm 56. These arms 56 and 62 are normally spaced apart a distance to provide a variable spark gap X and the minimum distance between these arms is maintained by means of a stop 63 which is fixed to the shell A for cooperation with the extension 60. The space between the terminal end of the arm 56 and the arm 61 forms a substantially constant gap Y. Thus when the engine is operated, the rod 58 which is formed of expansible metal will expand under the action of heat and cause the arm 62 to move away from the arm 56 thereby increasing the gap X while maintaining the gap Y substantially constant.

In the form illustrated in Figure 9, I have combined the structures shown in Figures 5 and 7 whereby both the central electrode 47 and the ground electrode 44 will be moved simultaneously in opposite directions to quickly vary the variable gap X but, however, without appreciably varying the constant gap Y.

I claim:

- 30 1. In a spark plug, a conducting portion and an insulating portion, and two electrodes respectively connected to said portions and normally forming two constantly open spark gaps of relatively smaller and larger sizes between said two electrodes, one of said electrodes being movable relatively to the other to increase the size of the smaller gap without varying the size of the larger gap.
- 40 2. In a spark plug, the combination with a conductor shell, of an insulator mounted therein and formed with a longitudinally and axially located recess extending from the inner end toward the outer end thereof, an electrode located within and extending longitudinally of said recess and having one end secured to the outer end of the insulator and having its other end projecting beyond the inner open end of the insulator, said electrode including a straight metal rod having a relatively high co-efficient of expansion and movable lengthwise under the influence of heat, guiding means for the inner end of the electrode for maintaining said inner end in spaced relation to the wall of the recess and for permitting longitudinal movement of the electrode, and an electrode secured to the shell for cooperation with the first mentioned electrode to form a spark gap therebetween.
- 45 3. In a spark plug, the combination with a conductor shell, of an insulator mounted therein and formed with a longitudinally and axially located recess extending from the inner end toward the outer end thereof, an electrode located within and extending longitudinally of said recess and having one end re-

movably secured to the outer end of the insulator and having its other end projecting beyond the inner open end of the insulator, said electrode including a straight metal rod having a relatively high co-efficient of expansion and movable lengthwise under the influence of heat, guiding means for the inner end of the electrode for maintaining said inner end in spaced relation to the wall of the recess and for permitting longitudinal movement of the electrode, said guiding means being mounted on the inner end of the rod for cooperation with the wall of the recess, and an electrode secured to the shell for cooperation with the first mentioned electrode to form a spark gap therebetween.

4. In a spark plug, a conducting portion and an insulating portion, and two electrodes respectively connected to said portions and normally forming two constantly open spark gaps of relatively smaller and larger sizes between said two electrodes, one of said two electrodes including a metal rod having a relatively high co-efficient of expansion and movable in a direction under the influence of heat to increase the size of the smaller gap without varying the size of the larger gap.

5. In a spark plug, a conducting portion and an insulating portion, a ground electrode connected to the conducting portion, and a central electrode connected to the insulated portion and movable longitudinally in response to temperature changes, said electrodes each including a shank and an inwardly extending and substantially radially disposed terminal arm, the arms being disposed in overlapping relation to form therebetween a variable spark gap, the terminal end of the arm of the ground electrode being spaced from the shank of the central electrode to form therebetween a substantially constant spark gap.

6. In a spark plug, the combination with a conductor shell, of an insulator mounted therein and formed with a longitudinally and axially located recess extending from the inner end toward the outer end thereof, an electrode located within and extending longitudinally of said recess and having one end secured to the outer end of the insulator and having its other end projecting beyond the inner open end of the insulator, said recess terminating at a point beyond the outer end of the shell and having a diameter greater than the diameter of the electrode to form an annular space between the wall of the recess and the electrode, an electrode secured to the shell for cooperation with the first mentioned electrode to form a spark gap therebetween, and a check-valve located within the recess at the inner end of the insulator and opening toward the closed end of the recess.

7. In a spark plug, the combination with a conductor shell, of an insulator mounted

- therein and formed with a longitudinally and axially located recess extending from the inner end toward the outer end thereof, an electrode located within and extending longitudinally of said recess and having one end secured to the outer end of the insulator and having its other end projecting beyond the inner open end of the insulator, said recess terminating at a point beyond the outer end of the shell and having a diameter greater than the diameter of the electrode to form an annular space between the wall of the recess and the electrode, an electrode secured to the shell for cooperation with the first mentioned electrode to form a spark gap therebetween, a perforated washer attached to the central electrode at the inner end of the insulator and having slidable contact with the wall of the recess, a valve slidably mounted on the central electrode for cooperation with the perforations of the washer, and a spring for yieldably retaining the valve against the washer.
8. In a spark plug, the combination with a conductor shell, of an insulator mounted therein and formed with a longitudinally and axially located recess extending from the inner end toward the outer end thereof, an electrode located within and extending longitudinally of said recess and having one end secured to the outer end of the insulator and having its other end projecting beyond the inner open end of the insulator, said recess terminating beyond the outer end of the shell and having a diameter greater than the diameter of the electrode to form an annular space between the wall of the recess and the electrode, an electrode secured to the shell for cooperation with the first mentioned electrode to form a spark gap therebetween, and a check-valve located within the recess at the inner end of the insulator and opening toward the closed end of the recess, the outer end of the central electrode being removably connected to the insulator to permit removal of the electrode together with the check-valve from the insulator.
9. In a spark plug, the combination with a conductor shell, of an insulator mounted therein and formed with a longitudinally and axially located recess extending from the inner end toward the outer end thereof, a fixed electrode secured to said shell, a movable electrode located within and extending longitudinally of the recess in said insulator and having one end secured to the outer end of the insulator and having its other end projecting beyond the inner open end thereof, the projecting end of said movable electrode cooperating with said fixed electrode to form two constantly open spark gaps of relatively smaller and larger sizes, said movable electrode including a straight metal rod having a relatively high co-efficient of expansion and movable lengthwise under the influence of heat to increase the size of the smaller gap without varying the size of the larger gap, and guiding means for the inner end of the movable electrode for maintaining said inner end in spaced relation to the wall of the recess and for permitting longitudinal movement of the electrode.
10. In a spark plug, the combination with a conductor shell, of an insulator mounted therein and formed with a longitudinally and axially located recess extending from the inner end toward the outer end thereof, a fixed electrode secured to said shell, a movable electrode located within and extending longitudinally of the recess in said insulator and having one end secured to the outer end of the insulator and having its other end projecting beyond the inner open end thereof, the projecting end of said movable electrode cooperating with said fixed electrode to form two constantly open spark gaps of relatively smaller and larger sizes, said movable electrode including a straight metal rod having a relatively high co-efficient of expansion and movable lengthwise under the influence of heat to increase the size of the smaller gap without varying the size of the larger gap, and guiding means mounted on the inner end of the rod for cooperation with the wall of the recess for maintaining said inner end in spaced relation to the wall of the recess and for permitting longitudinal movement of the movable electrode.
11. In a spark plug, the combination with a conductor shell, of an insulator mounted therein and formed with a longitudinally and axially located recess extending from the inner end toward the outer end thereof, an electrode located within and extending longitudinally of said recess and having one end secured to the outer end of the insulator and having its other end projecting beyond the inner open end of the insulator, the recess in said insulator terminating at a point beyond the outer end of the shell and having a diameter greater than the diameter of the electrode to form an annular space between the wall of the recess and the electrode, an electrode secured to the shell for cooperation with the first mentioned electrode to form a spark gap therebetween, and centering means cooperating with said first mentioned electrode and with said insulator to maintain said gap substantially constant.
12. In a spark plug, the combination with a conductor shell of an insulator mounted therein and formed with a longitudinally and axially located recess extending from the inner end toward the outer end thereof, an electrode located within and extending longitudinally of said recess and having one end secured to the outer end of the insulator and having its other end projecting beyond the inner end of the insulator, said recess terminating at a point beyond the outer end,

of the shell and having a diameter greater than the diameter of the electrode to form an annular space between the wall of the recess and the electrode, said electrode including a straight metal rod having a relatively high co-efficient of expansion and movable lengthwise under the influence of heat, guiding means for the inner end of the electrode for maintaining said inner end in spaced relation to the wall of the recess and for permitting longitudinal movement of the electrode, and an electrode secured to the shell for cooperation with the first mentioned electrode to form a spark gap therebetween.

15 In testimony whereof, I have hereunto subscribed my name.

WILLIAM OTTO MICHELSEN.
